UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,153,623.

Specification of Letters Patent. Patented Sept. 14, 1915.

Application filed April 1, 1909. Serial No. 487,355.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Gas-Producers, of which the following is a specification, accompanied by drawings forming a part of the same, in

10 which—

Figure 1 is a side elevation of my improved gas producer. Fig. 2 is a central vertical sectional view of the same on lines 2—2 of Figs. 3 and 4, showing the plow at 15 the left and the driving mechanism at the right in full. Fig. 3 is a plan view of the ash pan, and Fig. 4 is a plan view of the driving mechanism for rotating the ash pan.

Similar reference letters and figures refer 20 to similar parts in the different views.

My invention relates to a gas producer having a heating chamber with an inclosing wall divided into stationary and rotatable sections in order to prevent the caking of 25 the coal, and which is also provided with automatic means for removing the ashes from the bottom of the heating chamber, in order to maintain the zone of incandescence 30 of the coal in a uniform position and secure a regular and uniform combustion, and it consists in the construction and arrangement of parts as hereinafter described and pointed out in the annexed claims.

In the accompanying drawings I have 35 shown my improvements applied to a gas producer having a rotary ash pan, in which the ashes are deposited from the combustion chamber, with the ash pan of a larger diameter than said combustion chamber, and having 40 a flaring side with which a narrow blade is arranged to coöperate. In the gas producer, as shown in the drawings, the ash pan receives the ashes from the lower end of an ash hopper, supported by and rotating 45 with the ash pan. Above the ash hopper is a stationary gas producing chamber to which fuel is supplied in the usual manner. Air, to support combustion, is introduced in the lower part of the combustion chamber 50 through a central conduit.

Referring to the accompanying drawings, 1 is a combustion chamber of a gas producer inclosed in a stationary casing 2 supported

upon posts 3. The ash hopper 4 is supported upon feet 5 resting upon a central cone 6 of a rotating ash pan 7. Mounted upon the cone 6 is a hood 8, having slits or openings for the delivery of an air blast to the combustion chamber, said air blast being supplied through a central conduit 9. The ash pan is circular in plan view and is provided with a flaring side 10. The flaring side 10 and the central cone 6 form an annular ash receiving trough 10^a substantially triangular in cross section into which ashes fall from the ash hopper 4 and are accumulated in the angle between the side 10 and the cone 6. The flaring side 10 extends above the lower end of the ash hopper 4 forming an annular space through which ashes may be removed over the top of the flaring side 10. The ash pan is supported upon three rolls 11 having divergent shafts 12, which are journaled in bearings 13 supported upon piers 14.

The shaft 12 of one roll 11 is rotated by a worm gear 15 driven by a worm 16 connected with any convenient source of power, not shown. The inner end of the shaft 12, which carries the worm gear 15 on its outer end, is connected with the inner ends of the other two shafts 12 by bevel gears 17 and intermediate pinions 18, as shown in Fig. 4, thereby providing a positive drive for all three of the shafts 12 from the worm 16.

It is desirable for the most efficient operation of the gas producer that the zone of combustion be maintained at a predetermined vertical position relatively to the apex of the hood 8. If the zone of combustion be raised too high above the hood 8, a mass of ashes will accumulate upon the hood and check the free delivery of the air blast to the incandescent coal. If, on the other hand, the zone of combustion falls too low, it will include the hood 8, which will soon become burned out by the intense heat. The proper maintenance of the hot zone relatively to the hood 8 is accomplished by controlling the withdrawal of ashes from the ash pan. As the contents of the producer settle during the progress of combustion, ashes are forced from the lower end of the ash hopper into the ash pan, and accumulate in the annular space between the lower end of the ash hopper and the flaring side 10 of

the ash pan. If ashes are allowed to accumulate, they impede the free delivery of ashes from the ash hopper and cause the hot zone of the combustion chamber to be gradually raised.

By clearing the ashes from the ash pan the delivery of ashes from the bottom of the ash hopper is facilitated, and the hot zone in the combustion chamber gradually lowered. The removal of the ashes from the ash pan should be substantially uniform around the entire circumference of the ash hopper, to produce a uniform settling of the contents of the gas producing chamber.

In the case of gas producers having stationary ash pans where the ashes are removed by an attendant, by means of a hoe or shovel, uniform delivery of ashes has been difficult of accomplishment. It has, therefore, been proposed to accomplish the delivery of ashes from the ash pan by rotating the ash pan and interposing, in the path of the ashes carried thereby, a plow or blade having a warped surface and acting similar to a plowshare, to cause the ashes to be lifted as they are brought against it and carried over the edge of the ash pan by the warped surface of the plow. This method of removing ashes from a rotating pan has met with the objection that, as the ash containing space between the flaring sides of the ash pan and the central cone was V-shaped, it was difficult to remove clinkers from the bottom of the V-shaped trough without clearing out the entire ash pan of ashes, which was undesirable. If the plow was raised to obviate this objection, then the removal of ashes took place only from the top of the V-shaped trough and allowed the clinkers to accumulate at the bottom.

By my present invention, I accomplish the removal of clinkers from the bottom of the pan and control the removal of ashes with any desired degree of accuracy, whereby the zone of greatest combustion in the gas producing chamber is always maintained at a predetermined height above the apex of the hood 8. I accomplish this result by employing, in coöperation with the flaring side 10 of the ash pan, a comparatively narrow blade 19, with its under edge held parallel with the flaring side 10 of the ash pan as shown in Fig. 2. The blade 19 is attached to a head 20, which is arranged to slide in ways 21 on a plate 22 attached to one of the posts 3. A pinion 23 is carried on a spindle projecting from the head 20, and is arranged to engage a rack 24 on the plate 22 and to be rotatable by a hand wheel 25. By rotating the hand wheel 25, the blade 19 may be raised or lowered in a plane parallel with the side of the ash pan, thereby regulating the quantity of ashes removed from the ash pan by contact with the blade 19 and adjusting the speed of delivery. The head

20 is retained in the desired position by tightening the nuts 27.

The removal of ashes from the ash pan is accomplished as follows: The ash pan 7 is rotated in the direction of the arrow α , Fig. 3, and the ashes lying against the flaring side 10 of the ash pan are brought into contact with the blade 19, which is preferably slightly inclined in plan view by means of a bend at the point 26 bringing the blade 19 at an oblique angle to the path of the ashes as they are carried around by the rotating ash pan. The blade 19 preferably extends substantially to the bottom of the V-shaped trough formed between the central cone 6 and the flaring side 10 of the ash pan. The mass of the ashes contained in the pan will, of course, pass over the upper edge of the blade 19, but those striking against the side of the blade will be impeded in their forward movement and caused to slide upwardly upon the flaring side 10 of the ash pan and be delivered over its rim. The movement of ashes, which are impeded by their contact with the blade 19, takes place in the entire strata lying between the rim of the ash pan and the bottom of the V-shaped trough, so that the clinkers or other obstructive masses will be eventually dislodged at whatever depth they may be buried, and crowded upward against the flaring side 10 of the pan.

It has been found in practice that, in the operation of the gas producer, the interval between the stationary and rotating sections of the inclosing wall is gradually filled by clinkers, ashes, etc. In order to prevent this, I provide an annular plate 28, loosely suspended in a horizontal position from the stationary casing 2 upon a series of hooked supports 29, and arranged to be interposed between the top of the rotatable section 4 and the opposing wall of the stationary casing 2, in order to close the space and to prevent the passage of coal or clinkers over the top of the rotatable section 4.

Sufficient space must be provided between the top of the rotatable section 4 and the casing 2 to allow for the expansion of the walls of the sections 2 and 4, in addition to the thickness of the plate 28, and I regulate this space by the vertical adjustment of the rotatable section 4, which is accomplished as follows: Interposed between the ash pan which supports the rotatable section 4 and the rolls 11 is a ring 30, and wedges 31 are inserted between the bottom of the ash pan and the ring 30, by means of which the rotatable ash pan may be raised or lowered. When the adjustment is complete, the ash pan is secured in the proper position by tightening the bolts 32, connecting the ash pan and the ring 30. In order to enable the removal of ashes from the ash pan to be controlled independently of the vertical ad-

justment of the blade 19, I provide a curved plate 33 concentric with the rim of the ash pan and attached at its opposite ends to two of the posts 3. The plate 33 extends upwardly above the rim of the ash pan, and is provided with an opening 34 adjacent to the plate 22 which supports the blade 19. The concentric plate 33 is held in position to impede the flow of ashes over the rim of the ash pan, except as they are allowed to pass through the opening 34. The opening 34 may be partially closed by means of a sliding door 35, thereby controlling the delivery of ashes from the ash pan. This method of control of the ash delivery enables the blade 19 to be moved down to dislodge an accumulation of cinders from the bottom of the ash pan without increasing the flow of ashes over the rim of the ash pan. The ashes accumulated by the blade are checked by the plate 33, except as they are allowed to pass through the opening 34, and passing over the blade 19 are carried around by the ash pan.

25 I claim,

1. In a gas producer, the combination with a combustion chamber, of an ash hopper, an ash pan spaced below said hopper provided with flaring sides inclosing the lower end of said hopper, and a central cone forming a substantially triangular trough for ashes and a stationary narrow blade entering said trough, with one edge parallel with and contiguous to the flaring side of said ash pan, with the width of said blade less than the space between the flaring side of the ash pan and the opposing wall of the ash hopper.

2. In a gas producer, a combustion chamber, an ash pan spaced below said chamber provided with an annular trough for ashes triangular in cross section and having flaring sides, means for rotating said pan, a narrow stationary blade entering said annular trough, having parallel edges, with one of its edges in contact with the flaring side of the ash pan.

3. In a gas producer, a combustion chamber, an ash pan spaced below said chamber provided with an annular trough for ashes triangular in cross section, a narrow stationary blade entering said trough, with one of its edges in contact with the flaring side of the ash pan, and means for raising 55 and lowering said blade.

4. A gas producer, having a rotating ash pan, diverging shafts in the same horizontal plane beneath said ash pan, means carried by said shafts for supporting said pan and imparting rotation thereto, means for connecting the inner ends of said diverging shafts, and means for rotating one of said diverging shafts.

5. A gas producer, having a rotating ash pan, rolls supporting said ash pan, diver-

ing shafts in the same horizontal plane carrying said rolls, a bevel gear on the inner end of each diverging shaft, intermediate pinions connecting said gears, and means for rotating one of said diverging shafts. 70

6. A gas producer, having a heating chamber with an inclosing wall comprising a stationary and a rotatable section, and a single annular plate supported from said stationary section interposed between the bottom of said stationary section and the top of said rotatable section without contact with either section. 75

7. A gas producer, having a heating chamber with an inclosing wall comprising stationary and rotatable sections, and a single annular plate held in a horizontal position between said sections by hooked supports from said stationary section, but without contact with either section, to prevent the escape of material from the inside of said heating chamber. 80

8. A gas producer, having a heating chamber with an inclosing wall comprising stationary and rotatable sections, a single annular plate supported from said stationary section in a horizontal position between the bottom of said stationary section and the top of said rotatable section to prevent the escape of material from said chamber, and 90 with sufficient space between said plate and said stationary and rotatable sections to allow for the expansion of said sections.

9. A gas producer, having a heating chamber with an inclosing wall, comprising a 100 stationary and a rotatable section, an annular plate interposed in a space between said stationary section and the top of said rotatable section, and means for varying said space. 105

10. A gas producer, having a heating chamber with an inclosing wall comprising an upper stationary and a lower rotatable section, a single annular plate supported from said stationary section in a horizontal 110 position between said sections, with a space between said plate and said stationary and rotatable sections to allow for the expansion of said sections, and means for raising and lowering said rotatable section to vary said 115 space.

11. A gas producer, having a heating chamber with an inclosing wall comprising an upper stationary and a lower rotatable section, with a space between said sections 120 to allow for the expansion of said sections, and means for raising and lowering said rotatable section to vary said space.

12. A gas producer, having a heating chamber, comprising an upper and a lower 125 section, an ash pan below said lower section supporting said lower section, means for rotating said ash pan, and means for raising and lowering said ash pan.

13. A gas producer, having a heating 130

chamber, comprising an upper and a lower section, an ash pan below said lower section supporting said lower section, means for rotating said ash pan, means for raising and lowering said ash pan, and means for securing said ash pan as it is raised or lowered.

14. A gas producer, having a rotating ash pan with a flaring outer side, means for impeding the movement of ashes next said flaring outer side, whereby they are forced upwardly over the rim of the ash pan, and means concentric with the rim of said ash pan and extending upwardly therefrom for controlling the flow of ashes over said rim of the ash pan.

15. A gas producer, having a rotating ash pan with a flaring outer side, means for impeding the movement of ashes next said flaring outer side of the ash pan, a plate 20 extending above the ash pan having an opening for the delivery of ashes, and means for controlling the flow of ashes through said opening.

16. The combination with a rotating ash pan, of means for moving the ashes in said

pan upward over the rim of said pan, and means above said rim and concentric therewith for controlling the flow of ashes over said rim.

17. The combination with a rotating ash 30 pan, having a flaring outer side, of a blade for impeding the flow of ashes in said pan next said outer side, and means above said outer side and concentric therewith for controlling the flow of ashes over said outer 35 side.

18. The combination of a rotatable ash pan having a flaring outer side, a blade parallel with and adjacent to said flaring side, a plate concentric with said pan and extending above it, provided with an opening 40 for the delivery of ashes, and means for varying the size of said opening.

Dated this twenty fifth day of March 1909.

EBENEZER A. W. JEFFERIES.
